UNITED STATES PATENT OFFICE.

WILLIAM E. SCHILLING, OF DES MOINES, IOWA.

INTEREST-DETERMINING DEVICE.

Application filed July 15, 1922. Serial No. 575,240.

To all whom it may concern:

Be it known that I, WILLIAM E. SCHILLING, a citizen of the United States, and a resident of Des Moines, in the county of Polk and State of Iowa, have invented a certain new and useful Interest-Determining Device, of which the following is a specification.

The object of my invention is to provide 10 an interest determining device of very simple and inexpensive construction, which may be used for readily and easily determining the interest accrued at certain rates on certain sums between certain fixed dates 16 without the necessity for determining the elapsed time.

With this and other objects in view, my invention consists in the construction, arrangement and combination of the various 20 parts of my device, whereby the objects contemplated are attained, as hereinafter more fully set forth, pointed out in my claim, and illustrated in the accompanying drawings, in which:

25 Figure 1 shows a perspective view of an interest determining device embodying my invention.

Figure 2 shows a plan view of a portion of my device; and

30 Figure 3 shows a sectional view taken on the line 3—3 of Figure 2.

My improved interest determining device comprises primarily an envelope or receiving member indicated in the accompanying drawings by the reference numeral 10, having a sight opening 11 therein and a card 12 slidably mounted in said receiving member and adapted to be slid to different positions telescopically therein.

40 Adjacent to the sight opening 11 preferably at the left hand side thereof is a column of figures 11^a regularly spaced apart and running consecutively from "1" at the bottom to "31" at the top, as illustrated in

45 Figure 2. These figures represent the days of the month.

The sight opening 11 is preferably in the upper half of the receiving member.

At the upper end of the receiving member 50 is a thumb notch 13 for permitting the ready grasping of the card 12, when the latter is wholly received within the member 10.

Above the sight opening 11 are spaced sets of figures running from, for instance, 55 "10,000" to "90,000" arranged in horizontally

spaced columns. These columns are indicated by the reference numeral 14.

The card 12 is arranged with a series of horizontally spaced columns of figures 15, corresponding to the columns 14. The figures in the columns 15 are spaced apart vertically, distances corresponding to the distances between the numbers on the member 10, indicating the days of the month.

At the left hand side of the card 12 beginning at the top is a column 12^a of consecutively arranged figures running from "1" to "31", representing the days of the month and similarly spaced apart.

At the right hand side of the card 12 is a 70 column of figures running from "1" to "61" consecutively, similarly spaced apart and running from the bottom of the card to the upper portion thereof, this column being numbered 12^b.

On another card 12 the column 12^b may contain figures ranging from 62 to 122 inclusive, and on similar cards the columns 12^b may contain the remainder of the numerals corresponding to days in a year. 80

The columns 15 commence on a line, such a distance below the top of the card 12, as to allow for the space between the sight opening 11 and the top of the receiving element 10. 85

I provide a sufficient number of the cards 12 and members 10 to accomplish the purpose.

In the form of my device shown herein, I have shown each receiving member 10 with 90 two sight openings and designed to be used with two cards.

It is obvious that the receiving member 10 can be used to receive one card only, or more than two, if desired.

I preferably provide the backs of the receiving elements with sight openings and the backs of the cards with suitable tables, for the purpose of saving space.

Each card has on it the proper tables 100 showing the interest at a certain rate accruing between certain dates.

On the card 12, illustrated in the drawings, I have shown a table showing interest at six per cent for from one to sixty-one 105 days on various amounts.

I preferably attach to the members 10, tabs 16 on which may be printed the periods for which the cards held by that receiving member are to be used. For instance, the 110

card 12, illustrated, may be used for any period where the interest begins to run in a month having thirty-one days and ends in the next month. Other cards may be employed for the periods beginning in months having twenty-eight or thirty or thirty one days and ending in the next or any subsequent month.

For further illustration, it may be said that the figures on the card 12 are so arranged that when the card is slipped upwardly, for instance until the "1" at the upper left-hand side of the card in the column 12^a is just above the edge of the receiving member 10, then in the column of figures on the card 12 in the column corresponding to the column 14, having "10,000," there will appear, subject to corresponding placement of the decimal point, figures representing the interest on \$1.00, \$10.00, \$100.00, \$1000.00, \$10,000.00, and so forth, from the first of the month to the respective days of the succeeding month. For instance, opposite the numeral "1" in the column of days on the receiving member 10 will be found figures representing the interest on \$1.00, \$10.00, \$100.00, \$1000.00, or \$10,000.00, accrued from the first of one month to the first of the next month.

Horizontally across in the respective columns will appear the interest on \$2.00, \$20.00, \$200.00, \$2000.00 or \$20,000.00; on \$3.00, \$30.00, \$300.00, \$3000.00 or \$30,000.00; on \$4.00, \$40.00, \$400.00, \$4000.00 or \$40,000.00; on \$5.00, \$50.00, \$500.00, \$5000.00, or \$50,000.00; on \$6.00, \$60.00, \$600.00, \$6000.00 or \$60,000.00; on \$7.00, \$70.00, \$700.00, \$7000.00 or \$70,000.00; on \$8.00, \$80.00, \$800.00, \$8000.00 or \$80,000.00; and on \$9.00, \$90.00, \$900.00, \$9000.00 or \$90,000.00, the decimal point being correspondingly placed.

It will be seen that by properly pointing off the decimals, one may thus determine the interest on any sum from \$1.00 to \$99,999.00, or by enlarging the tables, the interest on any amount in excess may be similarly determined.

If for example, it is desired to find the interest on \$1532 on a note running from July 13th to August 31st, the user of the device would slide the card 12 upwardly until the numeral "13" representing the day of the month when the interest began to run, found in the column at the left-hand side of the sheet 12 stands just above the edge of the receiving member 10 (Figure 2).

Then the user runs down the column of days on the receiving member 10 at the left-hand side of the sight opening to the numeral "31" representing the last day of the month for which interest accrues; on running the eye across the page to the figures on the card in the column under \$10,000, and by properly placing the decimal point, finds the interest on \$1000, accrued between July

13th and August 31st, the figures shown opposite "31" being pointed off to read "\$8.167".

Running to the right across the columns 31 to the column headed on the receiving member 10 by "50,000" the user would similarly find the interest on \$500 accrued from July 13th to August 31st to be \$4.083, and this amount would be set down in a column under the \$7.00.

The user would thus have determined the interest of \$1500.

Going back to the column 14 under the heading "30,000", he would find in said column opposite the numeral 31 in the column of days, by properly placing the decimal point, the interest for \$30.00 for the period under consideration, to be \$.245 and place such amount under the interest already ascertained.

He would then look in the column below the "20,000" among the columns 14, at the point opposite the numeral 31 in column 11^a and by properly placing the decimal point, would find the interest on \$2.00 to be \$.016.

By adding up the various items of interest, the exact interest can be thus determined, the interest in the illustration on the amount of \$1532, totaling \$12.51.

In the column 12^b opposite the 31 in the column 11^a appears the number of days elapsed between July 13 and August 31st (49 days).

This process eliminates the necessity of determining the elapsed time, which is required, where the ordinary interest tables are used.

It also makes possible the finding of the interest on the whole sum from one card or sheet 12.

These cards may be used with tables at any rate of interest for any interval of time and the various containers 10 may be made to contain as many tables, as is desired.

I claim as my invention:

In a device of the class described, a receiving element having a sight opening in one of its top sides, a table of figures on said element adjacent to one of the vertical edges of the sight opening, said figures running from one at the bottom to thirty one at the top, said figures being equally spaced apart and representing days of the month, a column of figures on said element arranged adjacent the horizontal upper edge of the sight opening, said last column representing amounts of principal, said sight opening being arranged in the upper half of the receiving element, a card of greater length than the sight opening received in said receiving element and capable of sliding movement therein, a vertical column of figures on said card running from one at the top to thirty-one at the bottom, said last column of figures being in substantial alignment

with the column of figures on the receiving element running from one to thirty-one, a column of figures increasing successively from the bottom to the top and arranged on said card so as to be displayed along one edge of the sight opening, a plurality of columns of figures arranged vertically representing interest accrued for specified times on the amounts of principal specified in the horizontal column of figures on said receiving element, said card when moved to position partially out of the receiving element will bring the interest calculations to posi-

tion in horizontal alignment with the numbers along the vertical edge of sight opening 15 for a period of time starting with the number on the card just above the upper edge of the receiving element and said column of figures on the card arranged near one vertical edge of the sight opening, when aligned 20 horizontally with any of the numbers running from one to thirty-one on the receiving element, representing the elapsed time for which the interest is calculated.

Des Moines, Iowa, June 20, 1922.

WILLIAM E. SCHILLING.
